UNITED STATES PATENT OFFICE.

CHARLES W. FAIRCHILD, OF MINNEAPOLIS, MINNESOTA.

TOY HOUSE.

Application filed July 31, 1919. Serial No. 314,420.

To all whom it may concern:

Be it known that I, CHARLES W. FAIRCHILD, a citizen of the United States, resident of Minneapolis, county of Hennepin,

5 State of Minnesota, have invented certain new and useful Improvements in Toy Houses, of which the following is a specification.

This invention relates to improvements 10 in toy houses of the sectional or knock-down type.

An object of this invention is to provide an easily assembled and demounted toy house.

15 Another object is to provide a toy house which is a substantially rigid structure when assembled and which provides easy means of access to the house interior when the structure has been assembled.

20 Other objects of the invention will more fully appear from the following description and the accompanying drawings and will be pointed out in the annexed claims.

In the accompanying drawings, there has 25 been disclosed a structure to carry out the objects of the invention, but it is to be understood that the invention is not confined to the specific features shown as various changes may be made within the scope of 30 the claims which follow.

Figure 1 is a substantially isometric perspective of the house, showing the base, two walls and rods;

Figure 2 is a similar view with partitions 35 and floors added;

Figure 3 is a similar view of a later stage of assembly;

Figure 4 is a view showing the method of hanging an outside wall.

40 The major parts of this sectional house comprise broadly a base which may be a bottom floor or may be composed of base members, which assembled form the base or foundation; the upright members, which 45 term includes the outside walls and partitions; the transverse members, which includes the floors and the upper covering which may be simply the ceiling of the upper floor or a roof; the upright elements, 50 which in this selected embodiment of the invention are shown as rods upwardly extending through one or more floors; and the transverse elements which are here shown as rods horizontally extending across 55 the house structure. For convenience of reference the two outside walls shown in

Figure 1 may be termed the end walls, while the remaining outside walls may be termed the side walls of the house.

While various sheet materials may be employed in the fabrication of this structure, it is preferably formed of card-board or fibre-board.

While the foundation or base may be simply the bottom floor, it is preferably formed by the assembly of the side base members 1 and 2, and the joists 3. These joists are terminally secured to the side members 1 and 2 by means of L's 4, which may be detachably secured to the joists and to the side base members 1 and 2 by any suitable means, such as by an ordinary headed paper fastener or by bolt and nut, as shown.

In the structure here shown, base members are preferably omitted at the ends of the structure and the end walls 5 and 6 form the other two sides of the rectangular base here disclosed. The four corners of the thus-formed base are provided with corner bracket supports 7, detachably secured to the side base members and end walls and which are adapted to support the four corner upright elements. These upright elements are preferably formed of metallic rods 8 whose ends may be split, upset or terminally bent from their axis to prevent their being drawn completely through the apertures in their respective supports in assembling. Other upright rods 9 are provided also in the interior of the house to support the various parts and to attain increased strength and rigidity of the assembled structure. Three such rods 9 are here shown as held by U-shaped supports 28 secured to one of the joists 3, while additional upright rods may be added to support and brace different portions of the structure, such, for example, as a rod 10 provided to brace a particular partition and floor section. A transverse element such as a rod 11 extends across the base and projects through and beyond the end walls, the joists 3 and end walls being apertured to permit its passage therethrough. One end of this rod 11 may be headed or axially bent to engage one end wall and the other end may be provided with a demountable fastening such as is attained by threading a portion of the end and screwing a knurled nut thereon.

100 This transverse element imparts increased strength and rigidity to the base assembly.

This embodiment of the novel toy house discloses more than one floor, although obviously this invention comprehends a structure of one story or several. In Figure 2 the first floor 12 rests upon the base, being apertured to permit the passage therethrough of the upright rods. Ample support therefor is provided by the side members 1 and 2, the joists 3 and also by the top faces of the U-shaped supports 28 on the joists and of the corner bracket support 7. An upper floor 13 suitably apertured to permit passage of the rods may be supported and properly spaced from the lower floor by means of sleeves 14 slipped over the end of the upright rods, each sleeve being of a length equal to the spaced relation which it is desired that two contiguous floors have. Furthermore, a transverse element such as a rod 15 extends across the interior and, projecting through and beyond the end walls, is fastened in position similarly to the rod 11. This rod 15 functions to reinforce the assembled wall structure by binding the two end walls against the edges of the floors. Likewise, an upper floor 13 may be supported by means of the upper edge of partitions, such, for example, as the partition 16. Due to the fact that the floors are apertured to permit the passage therethrough of the plurality of upright rods, the floors are held against lateral movement. A convenient and easy mode of retaining a partition in place is afforded by means of the clips 17 secured to the interior face of a wall or to a floor and presenting a groove into which the edge of a partition may be introduced. A plurality of such partition clips 17 are shown on an end wall in Figure 1 and are shown, with the partitions in place, in Figure 2 wherein a floor clip 17 is also shown. Similarly, one partition 18 may be held in position by another partition 19 by means of such clips 17. Another mode of retaining partitions in position is afforded by means of loops 20 secured to the partitions and adapted to receive therethrough an upright rod, such, for example, as is shown on the median partition 21 in Figure 2. As here shown, a pair of loops 20 is secured adjacent to edge of the partition 19 while another pair is secured to the partition 21, both pairs receiving therethrough the rod 9. While the majority of the upright rods are shown as extending from base to the upper story of the structure, it is sometimes desirable to employ shorter upright elements, such as the rod 22, shown in Figure 2. This rod 22 extends only the distance of one floor as its function is to retain in position a pair of partitions on a single floor.

An upper transverse member or covering for the structure is shown in Figure 3,

although a further covering in simulation of a conventional roof is preferably added. In this figure the ends of the upright rods are shown with the threaded end portions bearing knurled nuts which are turned down upon their respective rods to exert a pressure on the covering to give the desired strength and rigidity to the structure.

It is desirable to afford easy access to the interior of the assembled structure in order that children in amusing themselves with it may place objects, such as toy furniture, in the various rooms. This is accomplished by making one or more of the outside walls quickly and easily demountable. To this end both side walls in this embodiment are hooked on and supported by the upper covering, while their lower portions are held against the adjacent base portions. As shown in Figures 3 and 4, the upper covering, which in this case is the upper transverse member forming the ceiling of the second floor, bears catches 23 adapted each to receive one of the hooks 24 secured to the side wall. The bottom portion of each side wall is clamped against the adjacent base member. For this purpose there are provided a plurality of sectional transverse rods. The end portions of each rod project beyond the base members which are apertured to permit their passage. These end portions are terminably bent to form clamping fingers 25 adapted to be turned to engage the lower edge portion of a side wall and clamp it against the adjacent base member, as shown on the left in Figure 3. The arrangement of these sectional rods is shown in Figure 1, wherein it may be seen that each is provided with a tension middle section. In the simple form disclosed it consists of an elastic member, such as a strip of rubber, secured at each end to a clamping section of a rod. The rubber strip being normally under tension exerts a constant force on the rod ends, tending inwardly to pull them and, hence, when the side walls are positioned, a tensioned clamping function is afforded to hold the side walls in position. Each wall may be removed by simply lifting it when the hooks disengage and the wall is likewise released from the clamps.

A roof 26 may be added and may be of the peaked type and rest upon the extended peaked tops of the end walls. Several transverse rods 27 are provided adjacent the top of the end walls, and, extending across the house, project through and beyond the opposed end wall. These rods are likewise bent at one end and threaded at the other to receive a nut which may be turned down to hold the end walls in a substantially rigid spaced relation and against the edges of the floors.

By the employment of the novel construction, a whole side of the house may be removed or even two sides and the roof, without interfering with or in any manner 5 weakening, the structural rigidity of the remainder. The parts are easily assembled and demounted without the use of any tools, the number of accessory parts is small, and the rigidity and durability are sufficient to 10 stand up well under the excessive wear and rough usage to which these toy houses are subject.

Having thus described my invention, what I claim as new and desire to secure by 15 Letters Patent is:

1. In a sectional toy house, the combination of a base, upright members, transverse members, rods connected to the base and upwardly projecting to support a plurality of 20 transverse members, and sleeves on said upwardly projecting rods to hold the transverse members in spaced relation.

2. In a sectional toy house, the combination of a base, outside walls, an upper transverse member, and co-operating means on an outside wall and on the transverse member whereby the outside wall is demountably suspended from said transverse member.

3. In a sectional toy house, the combination of a base, outside walls, an upper transverse member, co-operating means on an outside wall and on the transverse member whereby the outside wall is demountably suspended from said transverse member, and means on the base to hold said outside wall in position.

4. In a sectional toy house, the combination of a base, outside walls, an upper transverse member, means on an outside wall and the transverse member to support said wall

from said transverse member, and tension means to hold said wall in position.

5. In a sectional toy house, the combination of a base, side walls, end walls, an upper transverse member, means on said side walls and transverse member to support the side walls from said member, and clamping means on the base to hold the side walls in position.

6. In a sectional toy house, the combination of a base, outside walls, an upper transverse member, means on opposed walls to support the same from said member, sectional rods having opposed ends projecting beyond opposed sides of the base and terminally bent to engage the lower edge portions of said opposed walls, a tension section in each rod whereby the end portions of the rods are normally drawn inwardly 60 and the portions of the walls thereby tensionably held against the base.

7. In a sectional toy house, the combination of outside walls, and an upper transverse member, hooking means on the upper portion of one of the outside walls, and means on said transverse member engageable with said hooking means whereby said wall may be suspended from the transverse member and easily disengaged to expose the 70 interior of said house.

8. In a sectional toy house, the combination of a base, outside walls, transverse members and partitions, upright rods to secure the base and transverse members in 75 positioned relation, and means on the partitions to engage said rods to hold the partitions in positioned relation.

In witness whereof, I have hereunto set my hand this 25th day of July, 1919.

CHARLES W. FAIRCHILD.
